AIR PUMP

Linus E. Russell, Springfield, Ohio, assignor to
Peters & Russell, Inc., Springfield, Ohio, a cor-
poration of Ohio

Application February 14, 1949, Serial No. 846

Term of patent 14 years

(Cl. D65—1)

To all whom it may concern:

Be it known that I, Linus E. Russell, a citizen
of the United States, residing at Springfield,
Clark County, Ohio, have invented a new, origi-
nal, and ornamental Design for an Air Pump,
of which the following is a specification, reference
being had to the accompanying drawing, forming
a part thereof, in which Fig. 1 is a perspective
view of an air pump, embodying my new design;

Fig. 2 is a top plan view;
Fig. 3 is a side view; and
Fig. 4 is an end view.

I claim:

The ornamental design for an air pump, sub-
stantially as shown.

LINUS E. RUSSELL.
